(57) **CLAIM**

The ornamental design for a front light as shown and described.

DESCRIPTION

FIG. 1 is a view of the front light showing a first state;
FIG. 2 is a second state thereof;
FIG. 3 is a third state thereof;
FIG. 4 is a fourth state thereof;
FIG. 5 is a fifth state thereof; and,
FIG. 6 is a sixth state thereof.

The appearance of the front light sequentially transitions between the states shown in FIGS. 1-6. The process or period in which one state transitions to another forms no part of the claimed design.

The claimed design is indicated by dark lines and the relatively light portions within the dark lines in the figures. The de-emphasized and relatively light portions outside the dark lines form no part of the claimed design.
